VACUUM CLEANER CONSTRUCTION

Clarence A. Brock, Detroit, Mich., assignor to
Rexair, Inc., Detroit, Mich., a corporation of
Delaware

Original application December 18, 1935, Serial
No. 54,966. Divided and this application July
6, 1937, Serial No. 152,069

4 Claims. (Cl. 183—51)

This invention relates generally to vacuum cleaner constructions. The present application is a division of my prior co-pending application, Serial No. 54,966, filed December 18, 1935 and 5 assigned to the assignee of the present invention.

One of the primary objects of the present invention is the provision of a housing structure in which a removable compartment is provided which serves to collect the dust separated by the 10. mechanical separator and in addition, a compartment for housing the filter in order that this filter may be removed and cleaned from time to time when such is necessary or desirable.

In practice, it has been found that in vacuum 15 cleaner constructions of this general type, the mechanical separators provided serve to separate the dust present in the air being processed and only a relatively small percentage of the dust escapes the mechanical separator which dust is collected in the filter adjacent the discharge outlet 20 of the apparatus. In view of this situation, it has been found that only a small relatively compact filter is necessary and consequently, this filter may be disposed and housed entirely within the 25 casing and its removal and cleaning is necessary at only relatively infrequent intervals.

Many other and further objects, advantages, and features of the present invention will become clearly apparent from the following specification 30 when considered in connection with the accompanying drawings forming a part thereof.

In the drawings:

Figure 1 is a side elevational view of a vacuum cleaner construction embodying the improvements of the present invention.

Fig. 2 is a substantially enlarged vertical longitudinal sectional view of the vacuum cleaner construction shown in Fig. 1 illustrating one interior construction and arrangement of parts embodying the improvements of the present invention.

Fig. 3 is a transverse sectional view taken substantially on the line 3—3 of Fig. 2 illustrating the interior construction and arrangement of 45 parts of the improved vacuum cleaner construction on a slightly reduced scale.

Fig. 4 is a fragmentary sectional view taken substantially on the line 4—4 of Fig. 2 showing on a slightly reduced scale the mechanism for closing the filter compartment of the housing.

Fig. 5 is a transverse sectional view taken substantially on the line 5—5 of Fig. 2 on a slightly reduced scale illustrating the interior construction and arrangement of the filter compartment and 55 showing the filter bag mounted therein.

With more particular reference to the drawings, the specific embodiment of the invention shown therein comprises in general a casing 10 which may be formed of composite sheet metal or other suitable construction and which is illustrated as a 5 casting. The casing is preferably generally oval in shape and is provided in its central portion with a vertically extending partition wall 11. The casing as a whole is open at the top and is adapted to receive a suitable cover 12. This cover 12 is 10 provided with a flange 13 at its marginal edge adapted to mate with a corresponding flange 14 on the upper marginal edge of the casing 10.

On one side of the partition wall 11 in the casing 10 is mounted a blower housing 16 which 15 has mounted therein a suitable electric motor 17 serving to drive a plurality of centrifugal fans 18 which provide a multiple stage blower construction tending to draw air axially downward through the blower housing 16. The blower housing is provided at its upper end with an annular flange 19 which has a groove in the axial face thereof. A cover plate 20 has a grooved face adapted to mate with the grooved flange 19 and is secured thereto by means of a suitable annular 25 series of screws 21. A pair of partitioning members 23 and 24 have registering circular apertures therein slightly larger than the diameter of the flange 19 and associated cover plate 20, and have complementary circular grooves in their adjacent faces. An annular packing strip 25, having beaded edges, and preferably formed of rubber or suitable resilient composition, has one beaded edge clamped between the cover plate 20 and flange 19 by means of the screws 21 and has its 35 other beaded edge clamped between the partitioning members 23 and 24 and securely locked in place by means of bolts 26. It will be appreciated that the bolts 26 not only serve to lock the partitioning members 23 and 24 in predetermined position but also serve to interlock the flange 14 on the casing 10 to the flange 13 on the cover 12, thus securing the cover to the casing structure. Inasmuch as the partitioning members 23 and 24 have their marginal edges, throughout some considerable extent, exposed exteriorly of the casing, throughout this exposed area they may be provided with suitable finish moldings 28 to provide an attractive exterior appearance. A resilient padding element 66 may be secured to the lower 40 axial end of the motor in order to cushion this portion of the apparatus with respect to the casing 10, particularly when the machine is not in operation.

The cover plate 20 has mounted substantially 55

centrally thereof an annular series of ball bearings 30 in which is journaled a blower shaft 31. This blower shaft 31 is preferably directly connected to the electric motor 17 and serves to drive the vertical series of centrifugal fans 18 which tend to draw air downwardly through the blower housing. Surrounding the bearing structure 30 in the cover member 20 is an annular series of inlet apertures 32 which serve to permit the flow of air from the upper portion of the casing enclosed by the cover plate, downwardly into the multi-stage blower 18. Secured to the upper end of the shaft 31 of the blower, above the cover plate 20, is a mechanical dust separator element 35 adapted to be driven by the shaft.

While the element 35 may be formed in any convenient manner, it has been found preferable to construct it from a single, integral sheet metal stamping to provide a frusto conical structure having helically extending slots throughout substantially its entire peripheral surface as disclosed in detail and claimed per se in applicant's co-pending application Serial No. 152,070, filed July 6, 1937.

The dust separator element 35 is provided at its lower axial end with a radially extending flange 36 which is mounted on a suitable spider 38 secured to the shaft of the motor 31. It will be seen that as the motor 17 is run, air will be drawn inwardly through the slots in the separator element 35 by means of the centrifugal blowers 18 and dust in such air will impinge upon the rounded surfaces of the bars serving to define these slots and be centrifugally driven away. In order to insure that no dust-laden air will enter the necessary clearance between the dust separator element and the cover plate 20, a series of radially disposed vanes 37 are formed on the lower side of the spider 38. These vanes or blades act as a centrifugal fan and maintain a constant but relatively small outflow of air through this space, thus insuring that no dust-laden air will enter the interior of the dust separator element at this point. It will therefore be seen that all air which enters the interior of the blower housing will have been processed to remove the dust therefrom and that a much smaller, but equally constant outflow of air will be created by the vanes 37 operating in the clearance between the dust separator element and the cover plate 20, thus insuring that all air passing through the annular series of inlet ports 32 to the blowers will be substantially dust-free.

The casing 10 has an inlet opening 40 which may be formed integrally therewith and may be internally threaded to facilitate the connection of a flexible conduit 41 thereto which is adapted to be connected to any suitable nozzle, such for example as 42. An inlet duct 45 is connected to the inlet opening 40 and serves to provide communication between the inlet opening 40 and the space within the casing adjacent the dust separator element 35 above the partitioning members 23 and 24. This conduit 45 preferably extends arcuately around the electric motor 17 in the base of the casing and thence upwardly through suitable registering apertures in the partitioning members 23 and 24.

In the lower side of the casing on the opposite side of the partition wall from the portion in which the motor and blower are mounted, is a filter compartment generally designated as 50. Suitable louvers 51 are provided in the wall of the casing to permit the escape of air from the filter compartment 50. An outlet aperture is formed in

the partition wall 11 to provide communication between the compartment housing, the motor and blower, and the filter compartment and this aperture has preferably permanently mounted therein a nipple 55 which is adapted to receive a dust filter bag 56 of a shape conforming substantially to the shape of filter compartment 50. This filter bag 56 is preferably secured on the nipple 55 by means of a garter spring 57 or other suitable securing means. The filter compartment is closed at its upper side by means of a removable partition member 60 seated on a suitable gasket 61 and having one of its edges secured in a recess 62 formed in the casing 10. The opposite edge of this partition member 60 is retained in position by means of a spring element 63 secured to the partition wall 11 by means of a pair of bolts 64. This spring element 63 has a further important function which will hereinafter be clearly seen.

From the foregoing, it will be clear that dust-laden air taken in by the nozzle 42 will be conducted through the flexible tube 41 into the inlet 40. From the inlet 40 it will be conducted upwardly through the partition walls 23 and 24 into the upper portion of the casing in which is located the rotary dust separator element 35. It will be clear that the suction pressure generated by the multi-stage fan 18 driven by the electric motor 17 will draw this dust-laden air toward the separator element 35 and that the separator element will function to remove the air by centrifugal force, the dust particles, and will draw only substantially pure processed air downwardly through the blower housing. It will be seen that the only outlet for the air drawn into the blower housing is through the nipple 55 in the partition wall 11 and hence into the filter bag 56 secured thereto. The filter bag will, therefore, serve to collect any dust which was not extracted from the air by means of the centrifugal dust separator element 35 and consequently only substantially pure air will be passed from the filter compartment 50 out through the louvers 51.

A suitable circular aperture 70 is provided in the upper surface of the cover 12 and has surrounding it a packing member 71 upon which is seated a removably mounted glass cover panel 72 retained in position by means of a suitable frame 73. It will be clear that this cover panel 72 is sufficiently large in order that access may be had to the rotatable dust separator element 35 and that this element may be cleaned, adjusted, dismounted or replaced at will without disturbing the mounting of the cover 12 on the casing 10.

As may be desired, a handle 74 may be suitably secured to the top of the cover member 12 in order to provide convenient means for transporting the dust separating apparatus from place to place. The opposite end of the cover section 12 to that in which the rotary dust separator element is mounted is partitioned off by means of an integrally formed partition wall 76 which mates with the partition member 23 to provide a closed compartment at the upper end of the dust separator cover. In this compartment is mounted a suitable terminal block 77 to which is connected a cord 78 adapted to connect the dust separator with a suitable source of electric current. Also mounted within this compartment is a suitable switch 79 which serves to provide means by which the electric motor may be started and stopped. Connection wires 80 extend from the switch 79 and connector block 77 down to the electric motor 17.

In the space between this portion of the cover 75

section 12, just described, and the upper surface of the filter compartment 50, is located a removable slidably mounted dust bin 85. This dust bin 85 preferably has an exterior face provided 5 with a suitable handle 86 and mates closely with the adjacent walls of the casing 10 and cover 12. The upper marginal edge of the dust bin is preferably beaded and provided with a finish molding 88 which, when the dust bin is slid into position, 10 will mate with the finish molding 28 on the lower partition member 24 to provide a substantial continuation thereof which it will be seen extends entirely around the dust separator casing. The drawer or dust bin 85 preferably extends substantially 15 the full width of the casing 10 and the under side of the partition member 23 is preferably provided with a resilient sealing strip 90 seated therein throughout the extent which this partition element mates with the drawer in order to provide an effective and tight seal of the partition member 23 with respect to the top marginal edge 20 of the bin 85. The rear wall of the bin on its exterior side substantially in the central portion thereof is provided with a spearhead 91 preferably 25 formed integrally with the drawer and adapted to enter between the spaced prongs 92 of the spring element 63. These prongs 92 are preferably formed by bending suitable lateral projections on the spring element 63 between the points 30 at which this spring element is secured to the partition wall 11. It will thus be appreciated that the dust bin 85 is maintained in predetermined position with respect to the casing in which it is mounted and that it is locked in position by means 35 of the spring element 92 and the mating spearhead 91. It will further be seen that the top marginal edge of this drawer is effectively sealed by means of the resilient sealing element 90.

A suitable aperture 95 interconnects the portion 40 of the casing in which the bin 85 is mounted with the portion of the casing surrounding the rotary separator element 35. Due to the centrifugal action of the rotary separator element 35 the dust particles in the air entering the portion 45 of the casing in which this element is located will be driven to that portion farthest away from the rotary separator element 35 and will consequently drop directly into the dust bin 85. From the foregoing, it will be appreciated that as the nozzle 42 serves to draw dust from articles being cleaned, 50 this dust will be conveyed through the inlet 40 and intake conduit 45 into the chamber surrounding the rotary dust separator element. At this point the dust particles will, by means of the 55 rotary dust separator, be separated from the air and will drop into the bin 85. The clean air passes downwardly through the multiple stage blower and out through the filter bag 56 which serves to subject the air to further cleaning action. From the construction described above, it 60 will be apparent that the dust bin 85 may be conveniently removed whenever it is desired by bodily separating it from the casing 10. Accumulated dust, therefore, may be emptied from the bin 85 at convenient intervals without in any way dis- 65 assembling the machine.

At certain times it is found desirable to use a machine of this general type for providing a blast of air for various cleaning operations and other 70 purposes. In order to conveniently effect this result, the filter compartment is provided with an aperture 100 internally threaded in substantially

the same size and manner as the inlet aperture 40. In normal operation of the machine, this aperture 100 may be left open as may be desired and some of the exhausted air from the dust separator will be discharged therethrough. However, 5 the greater portion of the exhausted air will pass outwardly through the louvers 51.

Many other and further modifications of the invention falling within the scope of the subjoined claims will be apparent to those skilled in the art. 10

What is claimed is:

1. In a dust separator, an enclosed casing, a compartment in said casing, mechanical dust separating means within said compartment, a filter compartment in communication with said first mentioned compartment, a filter bag removably mounted in said filter compartment, a recess in said casing adjacent said filter compartment communicating with said first mentioned compartment, a receptacle removably mounted in said recess adapted to accumulate dust from said mechanical dust separating means, and means within 15 said recess providing access to said filter compartment when said receptacle is removed from said casing. 25

2. In a dust separator, an enclosed casing, a compartment in said casing, mechanical dust separating means within said compartment, a filter compartment in communication with said first mentioned compartment, a filter bag removably 30 mounted in said filter compartment, a recess in said casing adjacent said filter compartment, communicating with said first mentioned compartment, a receptacle removably mounted in said recess adapted to accumulate dust from said mechanical dust separating means, and a removable 35 panel within said recess separating said recess from said filter compartment and providing access thereto when said receptacle is removed.

3. In a dust separator, an enclosed casing, a compartment in said casing, mechanical dust separating means within said compartment, a filter compartment in communication with said first mentioned compartment, a filter bag removably 40 mounted in said filter compartment, a recess in said casing adjacent said filter compartment communicating with said first mentioned compartment, a receptacle removably mounted in said recess adapted to accumulate dust from said mechanical dust separating means, a removable 45 panel separating said recess from said filter compartment providing access thereto when said receptacle is removed and spring means within said casing serving to lock said panel and receptacle in position within said casing. 55

4. In a dust separator, an enclosed casing, a compartment in said casing, mechanical dust separating means within said compartment, a filter compartment in communication with said first mentioned compartment, a filter bag removably 60 mounted in said filter compartment, a recess in said casing adjacent said filter compartment communicating with said first mentioned compartment, a receptacle removably mounted in said recess adapted to accumulate dust from said mechanical dust separating means, a removable 65 panel separating said recess from said filter compartment providing access thereto when said receptacle is removed, and a spring element engaging both said panel and receptacle in position 70 within said casing.

CLARENCE A. BROCK.
